UNITED STATES PATENT OFFICE.

SAMUEL C. EVANS, OF NEW CASTLE, PENNSYLVANIA.

FURNACE.

1,388,810.

Specification of Letters Patent. Patented Aug. 23, 1921.

Application filed November 21, 1919. Serial No. 339,639.

To all whom it may concern:

Be it known that I, SAMUEL C. EVANS, a citizen of the United States, residing at New Castle, in the county of Lawrence and State of Pennsylvania, have invented new and useful Improvements in Furnaces, of which the following is a specification.

The object of my present invention is the provision of a furnace designed more particularly for use in tin and sheet metal mills, and adapted to afford a mellow heat with a view to giving the plates a uniform surface, and this with the consumption of a minimum amount of fuel and in such manner as 15 to avert material scrap waste.

My novel furnace is also advantageous in that it takes up but little space, and requires but a minimum quantity of brick in its construction; and to the attainment of the foregoing, the invention consists in the improvement as hereinafter described and definitely claimed.

In the accompanying drawings, hereby made a part hereof:

25 Figure 1 is a horizontal section of my novel furnace taken on the line 1—1 of Fig. 2.

Fig. 2 is a view, partly in front elevation and partly in transverse section of the furnace.

30 Fig. 3 is a longitudinal section on the line 3—3 of Fig. 2.

Fig. 4 is a rear elevation of the furnace.

Similar numerals of reference designate 35 corresponding parts in all of the views of the drawings.

The major portion of my novel furnace is constructed of refractory material, and among other elements the furnace comprises 40 a grate 1, fire-doors 2 and longitudinal combustion chambers 3 that extend rearwardly in parallel relation from the upper portions of the space above the grate 1. The furnace also comprises a hearth chamber 4, vertically disposed flues 5 for products of combustion, and air flues 6, relatively arranged as illustrated. At 7 is a damper controlled uptake, and at 9 and 10 are furnace doors, the doors 45 being at the rear. In this connection it 50 will be appreciated that the furnace may

be operated by using the rear doors 10 which will eliminate much hard labor when a platform is provided adjacent to the rear end of the furnace, in conjunction with a conveyer disposed alongside the furnace to 55 carry the tin plate.

It will be manifest from the foregoing that the charging door or doors 10 at the rear of my novel furnace constitute important features of my invention. This will 60 be better appreciated when it is stated that my novel furnace is charged through the rear door or doors 10, and the plates are withdrawn through the door or doors 9. In charging the improved furnace the operator catches hold of the loose end of the pack and in consequence the said loose end is farthest from the "rash" fire. In withdrawing through the door or doors 9 the operator catches hold of the curled end of 70 the pack. By virtue of this the packs cannot open and scrape the bottom of the chamber 4.

The longitudinal combustion chambers or 75 hot air flues 3 of my improved furnace assure the ignition of the gases in the smoke thereby affording a clear flame which of course has a tendency to improve the quality of the sheet metal.

Having described my invention, what I 80 claim and desire to secure by Letters-Patent, is:

In a furnace a hearth or working chamber having doors at its front and rear ends, a grate at the rear of the furnace, an uptake 85 leading from the hearth or working chamber at a point adjacent to the rear end of the furnace, means below the hearth or working chamber to conduct the products of combustion from the space above the grate to the 90 forward end of the hearth or working chamber, and an air flue arranged transversely below and connected with the said conducting means at a point slightly in front of the grate, all in combination and for the purpose set forth.

In testimony whereof I affix my signature.

SAMUEL C. EVANS.
